UNITED STATES PATENT OFFICE

CALVIN N. COLPITTS, OF MALDEN, MASSACHUSETTS, ASSIGNOR TO AMERICAN WINDOW SHADE MACHINE COMPANY, OF BOSTON, MASSACHUSETTS, A CORPORATION OF MASSACHUSETTS

EYELET FEEDING MECHANISM FOR EYELET SETTING MACHINES

Application filed November 15, 1930. Serial No. 495,934.

This invention relates to eyelet-setting machines and particularly to the eyelet-feeding mechanism by which the eyelets are fed individually to the eyelet-setting devices. The 5 invention is shown as applied to a combined drill and eyelet-setting device of the type illustrated in my co-pending application Serial No. 483,416, filed September 22, 1930. The machine illustrated in said application is designed to set eyelets or grummetts in a curtain shade and is constructed to first drill a hole through the stick in the bottom hem 10 of a window shade and as part of the same operation to set an eyelet in the drilled hole. The invention, however, is not limited in its use to the particular form of eyelet-setting machine illustrated in said application.

In order to give an understanding of the invention I have illustrated in the drawings a selected embodiment thereof which will now be described after which the novel features will be pointed out in the appended claims.

In the drawings:

Fig. 1 is a view showing a portion of a combined drill and eyelet-setting machine of the type illustrated in my above-mentioned application Serial No. 483,416 and illustrating my improved eyelet-feeding mechanism;

Fig. 2 is a reduced section through the hopper on the line 2—2, Fig. 3;

Fig. 3 is an enlarged view of the hopper mechanism taken at right angles to Fig. 1;

Figs. 4 and 5 are views taken on the line 4—4, Fig. 3 and illustrating the means for oscillating the agitating brush;

Fig. 6 is a similar view showing the position of the parts when the brush is thrown out of operation;

Inasmuch as the present invention relates to the eyelet-feeding mechanism by which the eyelets are delivered from the hopper or magazine into position to be set, I have not thought it necessary to illustrate herein the entire machine for drilling the hole and setting the eyelet therein but have contented myself with showing only a sufficient part of the machine to enable the present invention to be understood.

1 indicates generally a portion of the

frame of a combined drill and eyelet-setting machine on which is mounted a drill spindle, similar to that shown in my above-mentioned application, and one end of which is indicated at 2. This drill spindle carries a drill 3 and is adapted for rotation and vertical movement in order to drill a hole in the stick at the lower end of a window shade. In the drawings the window shade is shown in section at 4 and the lower end which receives the stick and in which the hole is drilled by the drill 3 is indicated at 5.

The machine also includes a hopper 6 for receiving eyelets 7 and a raceway 8 by which the eyelets are delivered from the hopper 6 into position to be set. The raceway 8 is so designed and constructed that the eyelet 7a at the lower end thereof will be in line with the drill so that as the drill spindle is lowered the drill will pass through the eyelet 7a and into the stick at the end of the curtain thereby to drill a hole therein. After the drill has entered the eyelet the raceway is moved backwardly into the dotted line position Fig. 1 in a manner similar to that described in the above-mentioned application and as the drill spindle continues its downward movement the end thereof, indicated at 2 in Fig. 1, forces the eyelet through the drill hole and co-operates with an anvil member 9 to set the eyelet. These operations are described more completely in the application above referred to.

As stated above the present invention relates to the construction of the hopper and the raceway and the means for delivering the eyelets singly from the hopper to the raceway.

The hopper or magazine 6 is preferably supported in an inclined position as shown and is provided in its bottom with an eyelet-receiving groove 10 of a width to receive the shanks of the eyelets 7 but of less width than the diameter of the heads 11 of the eyelets. This eyelet-receiving slot 10 communicates at one end with the raceway 8. The latter is provided with a channel 12 of a size to receive the heads 11 of the eyelets and with a slot 13 in its under face which is aligned with the slot 10 and is adapted to receive the

shanks of the eyelets. Any eyelet which is placed with its shank in the slot 10 as shown at the left in Fig. 2 will gravitate toward the lower end of the slot and from the lower end into the open upper end of the slot 13 of the raceway. The eyelets will then gravitate down the raceway toward the lower end thereof.

The raceway is so constructed that the eyelets are delivered into the upper end of the raceway in an upright position, that is, with their heads at the upper ends and the shanks depending from the heads, and the lower end of the raceway is so shaped and designed that the bottom eyelet 7a will be in an upright position axially aligned with the drill 3. It will be understood that the raceway is provided with suitable means at its lower end for retaining the end eyelet 7a in position but for allowing it to be withdrawn from the raceway when the latter is swung into dotted line position as shown in the above-mentioned application.

The eyelets are deposited in the hopper 6 through an opening in the top thereof, which is adapted to be closed by a hinged cover member 14 and as they are thus deposited they will have indeterminate positions in said hopper.

Situated within the hopper is an oscillatory brush by which the eyelets are kept agitated, the agitation resulting in the deposit of eyelets in the eyelet-receiving slot 10. This brush comprises a head 15 having radially arranged tufts 16 of bristles. The brush is situated at the bottom of the hopper so that the bristles wipe over the peripheral portion of the bottom as the brush is oscillated. The brush is mounted on a shaft 17 which extends through the bottom of the hopper 6 and is journaled in a bearing member 18 extending from the under side of the hopper.

As stated above the brush is given an oscillatory movement for the purpose of keeping the eyelets 7 agitated and this oscillatory movement is derived from a shaft 19 which is driven by some suitable driving mechanism and which carries the cam that controls the up and down movement of the drill spindle in a manner similar to that shown in my said co-pending application Serial No. 483,416. This shaft 19 carries a disk 20 at its end which is provided with a cam projection 21 which co-operates with two arms 22, 23 extending laterally from the shaft 17. The two arms 22 and 23 are arranged one above the other and also have an angular relation as shown in Figs. 4 and 5.

Assuming that the head 20 is rotating in the direction of the arrow Fig. 3 the cam projection 21 will engage the arm 22 while said cam projection is passing through the upper arc of its movement and during such engagement the shaft 17 will be given a partial rotation. As the head 20 continues its

rotative movement the cam projection 21 will wipe by the arm 22 and when said cam projection is passing through the lower arc of its movement it will engage the arm 23 and will turn the shaft back to its initial position. 70

Fig. 4 shows the position of the parts corresponding to that in Fig. 3 with the cam projection 21 just engaging the arm 22 while said projection is passing through the upper arc of its travel. This engagement will turn 75 the shaft 17 from the position shown in Fig. 4 to that shown in Fig. 5. When the disk 20 has made about a half rotation from the position shown in Fig. 3 the projection 21 will engage the arm 23 as shown in Fig. 5 and as 80 the head 20 continues to rotate the shaft 17 will be returned to the position shown in Fig. 4. The shaft is thus given an oscillatory movement during which the tufts 16 of bristles agitate the eyelets 7 and during such agitation some of the eyelets will become deposited in the groove 10 as shown in Fig. 2. 85

I have provided means for rendering the brush-oscillating mechanism inoperative whenever the eyelets begin to accumulate in 90 the groove 10 faster than they are being used. The shaft 17 has fast thereto a collar 25 provided with a handle 26. By means of this handle the shaft may be turned into the position shown in Fig. 6 wherein the arms 22 and 23 are located at the opposite side of the shaft 17 from the disk 20. With the arms 22 and 23 in this position the disk 20 will rotate freely without giving an oscillatory movement to the shaft. 100

The shaft may be held in this inoperative position by means of a spring-pressed ball 27 which is mounted in a recess 28 formed in the boss 18 and which is adapted to engage a notch 29 formed in the collar 25. There are 105 two notches 29 situated on opposite sides of the collar and one of the notches will be in position to receive the ball 27 when the handle 26 is turned into the position shown in Fig. 6 whereby the shaft will be held in this inoperative position. When the shaft is given a half rotation the other notch 29 will come in line with the ball 27 but in this position the shaft is oscillated back and forth by the cam projection 21 and during this oscillating movement the ball 27 will click into and out of the notch 29. 110

The hopper 6 is shown as having a bracket member 30 rigid therewith which is pivoted to the frame at 31 to allow the hopper and raceway to swing slightly for the purpose of moving the end of the raceway from the full to the dotted line position Fig. 1 during the eyelet-setting operation in a manner similar to that shown in my copending application 115 Serial No. 483,416. 120

I claim.

1. In an eyelet-setting machine, the combination with an eyelet-containing hopper, of a raceway communicating therewith, an os- 130

5 cillatory brush in the hopper for agitating the eyelets, an oscillatory shaft on which the brush is mounted, an actuating shaft situated at right angles to the oscillatory shaft, two arms extending from the oscillatory shaft at different angular positions, a cam projection on the actuating shaft which engages the arms alternately as the actuating shaft rotates, thereby to oscillate said oscillatory shaft, and means to turn the oscillatory shaft into a position in which the arms are out 10 of the path of movement of said cam projection.

15 2. In an eyelet-setting machine, the combination with an eyelet-containing hopper, of a raceway communicating therewith, a brush in the hopper for agitating the eyelets, an oscillatory shaft on which the brush is mounted, an actuating shaft situated at right 20 angles to the oscillatory shaft, two arms extending laterally from the oscillatory shaft at different points axially of the shaft, and a cam projection on the actuating shaft adapted to engage said arms alternately as the actuating shaft rotates thereby to oscillate the 25 oscillatory shaft.

In testimony whereof, I have signed my name to this specification.

CALVIN N. COLPITTS.
